[57] CLAIM

The ornamental design for a combined seat and life preserver cushion, as shown and described.

DESCRIPTION

FIG. 1 is a front elevational view of the combined seat and life preserver cushion showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is an isometric view showing the seat with the life preserver cushion detached and in reverse condition for illustrative purposes.

*FIG. 1**FIG. 2**FIG. 3*
